(57) CLAIM

The ornamental design for a shoe as shown and described.

DESCRIPTION

FIG. 1 is a front perspective view of a shoe showing my new design;
FIG. 2 is a side view thereof;

FIG. 3 is an opposite side front perspective view thereof;

FIG. 4 is an opposite side view thereof; and,

FIG. 5 is a top view thereof.

The even-length broken lines within the shaded region represent stitching that forms no part of the claimed design. The five uneven length broken line circles within the shaded area represent eyelets that form no part of the claimed design. The uneven length broken lines in the front-central region represent a lace loop and surround that form no part of the claimed design. The uneven length broken lines depicting the remainder of the shoe form no part of the claimed design.
